UNITED STATES PATENT OFFICE

167,242

AIR SPEED INDICATING DEVICE

Louvan E. Wood, Baltimore County, Md., assignor
to Bendix Aviation Corporation, Baltimore,
Md., a corporation of Delaware

Application April 16, 1952, Serial No. 19,356

Term of patent 14 years

(Cl. D52—1)

To all whom it may concern:

Be it known that I, Louvan E. Wood, a citizen of the United States, residing in the county of Baltimore, in the State of Maryland, have invented a new, original, and ornamental Design for an Air Speed Indicating Device, of which the following is a specification, reference being had to the accompanying drawings, forming a part hereof.

In the drawing:

Figure 1 is a perspective view of an air speed indicating device showing my new design;

Figure 2 is a side elevational view of the apparatus shown in Figure 1; and

Figure 3 is a rear elevational view of the apparatus shown in Figure 1.

I claim:

The ornamental design for an air speed indicating device as shown.

LOUVAN E. WOOD.
